UNITED STATES PATENT OFFICE.

FREEMAN HANSON, OF HOLLIS, MAINE.

WOOD-TURNING MACHINE.

SPECIFICATION forming part of Letters Patent No. 235,526, dated December 14, 1880.

Application filed May 21, 1880. (No model.)

To all whom it may concern:

Be it known that I, FREEMAN HANSON, of Hollis, in the county of York and State of Maine, have invented a new and useful Improvement in Wood-Turning Machines, of which the following is a specification.

The object of my invention is to control the path described by the rotating wood in a wood-turning machine, and hence the shape of the object cut, by means of geared pattern-wheels or formers of any desired shape, which are made to revolve in unison with and describe the same path as the wood itself. The mechanism by which this is done is shown in the accompanying drawings.

Figure 1 is a top plan. Fig. 2 is a front elevation. Fig. 3 is an end view showing two positions of the cutting mechanism. Fig. 4 is a detail of the slotted uprights and bearings. Fig. 5 is a detail of the geared pattern-wheel and the small gear which moves it.

The same letters refer to similar parts in the different drawings.

A is the table or frame-work, which supports the moving parts of the machine. B is a pulley on the driving-shaft a , and serves to impart motion to the apparatus. It is connected by the belt b with the pulley B' on the shaft a' , which turns in the bearings c c' , fastened to the frame-work. The shaft a' carries a pulley, B^2 , which rotates the cutting device by means of the belt b' , as hereinafter explained. It also supports the rods d d' of the cutting mechanism, but allows them to rock back and forth, as hereinafter explained. The shaft a' also carries the cone-pulley B^3 , which is connected by the belt b^2 with a corresponding cone-pulley, B^4 , on the shaft a^2 .

C C' are slotted uprights or posts fastened to the frame-work A, the slots e e' , Figs. 3 and 4, running longitudinally nearly the height of the posts, and serving to hold the bearings c c' , in which the shaft a^2 turns, and act as guides for the movable bearings c^2 c^2 , as hereinafter explained.

The shaft a^2 is provided at each end, near the bearings c c' , with a small gear-wheel, g g' , which acts upon the pattern-wheels or formers D D, which are carried on the shaft a^3 .

The shaft a^3 turns in the movable bearings c^2 50 c^2 , which slide up and down in the slots e e' of the posts C C'. The two pattern-wheels are made of the same size and shape, and have geared or toothed outlines, which are acted upon by the gear-wheels g g' , as before stated, 55 which are also duplicates of each other. The end of the shaft a^3 toward the cutting mechanism terminates in a flat surface or chuck, f , which is provided with short prongs h h' , and serves to hold one side of the wood to be operated upon.

The arm i projects from the top of the movable bearing c^2 in the post C' over the wood. After extending horizontally a distance large enough to allow the insertion of wood of the required thickness, the arm i bends downward, and is provided at its lower end with the revolving collar j , through which passes the set-screw or holder k , which presses against the wood held by the chuck f , and thus holds it 70 firmly against the chuck f and prongs h h' without interfering with its rotation.

It is obvious that many other devices which would hold the wood without interfering with its rotation might be used instead of that shown 75 in the drawings.

No other support than the gear-wheels g g' is provided for the pattern-wheels D D and shaft a^3 , and thus it is evident that the pattern-wheels are held in contact with the gears 80 g g' by force of gravity, acting on the whole weight of shaft a^3 , wheels D D, bearings c^2 c^2 , wood-holding device, and the wood itself. Consequently the rotation of the shaft a^2 and its gears g g' will raise this whole mass against 85 the action of gravity, or allow it to fall accordingly as the teeth engaged by these gears are on the longer or shorter radii of the pattern-wheels D D, when they are made of oval or polygonal shape, or, in fact, any shape other than circular. Every revolution, then, of these oval or polygonal wheels D D will raise the wood to be operated upon as many times as the wheels have longer radii, and lower it as many times as the wheels have shorter radii. 90 Thus the wood will be made to rotate, and in rotating describe the path taken by the pattern-wheels D D; but in order to secure a 95

smooth and even motion of the wood, and hence of the pattern-wheels D D, the weight of the latter and the mechanism connected with them does not come upon the teeth of the gears g g, 5 in which case, by imperfect engagement of the teeth the motion might become uneven, and thus the finish of the wood be destroyed. To avoid this, the pattern-wheels D D and gears g g are provided with smooth surfaces at each 10 side of the row of teeth, as shown in Fig. 2, and it is upon these smooth surfaces that the weight referred to falls. Between these two smooth strips of surface, on the gears g g, is a row of projecting teeth, while between the corresponding surfaces of the pattern-wheels is a 15 row of sunken teeth. The projecting-teeth of the gears g g, as shown in Fig. 5, do not reach the bottom of the spaces between the teeth of the pattern-wheels, and hence no weight comes 20 upon the engaging teeth, which thus turn the pattern-wheels without regard to their weight.

Though I consider gravity as the most convenient force to be used to hold the geared pattern-wheels in contact with the gears on the 25 stationary shaft, other forces may be used, if desired, such as weights and pulleys. In such cases the pattern-wheels D D are to be placed at the side of the gears g g instead of above, and the movable shaft a^3 slides horizontally 30 instead of vertically.

It is evidently not necessary that the pattern-wheels should be regular in their outline, the only thing required being that the angles should not be sharp enough to interfere with 35 their rotation. The outlines are necessarily geared or toothed to prevent slipping back, the force of gravity being continually exerted to keep the bearings $c^2 c^2$, &c., at the lowest point of their path. Neither is their number 40 limited to two, as it may be desirable to increase the number for very heavy work, and for very light work a single pattern-wheel may suffice.

The cutting mechanism consists of the two 45 rods d d', which rock back and forth, and, as before mentioned, are supported by the shaft a' , the short shaft or arbor a^4 joining these two rods and rotated by the pulley B³, which is connected by the belt b' with the pulley B², 50 as before stated, and the cutter-head l, which is carried on the arbor a^4 , and to which the knife or chisel is fastened. The rods d d' are fastened together by the cleats m m, and the rod d' is provided with a handle, n, by which 55 the whole cutting mechanism is shifted into its different positions, as shown in Fig. 3.

The stop p slides in guides on the under side of the table A, and is used to hold the cutting mechanism at any desired distance 60 from the wood or entirely away from it, in the position shown by the dotted lines of Fig. 3, when desired. It is provided with a longitudinal slot, e², by means of which and the binding-screw o and thumb-screw q it may be held 65 at any desired point of its slide. The stop p

is also provided at one end with the cut or opening r, which allows the stop to reach the upper cleat, m, and thus move the cutting mechanism without interfering with the motion of the belt b'.

The operation of the machine is as follows: The wood, which may be of any desired size and thickness, is held between the chuck f and holder k, as before stated. The machine is then started and the cutting mechanism 70 brought into contact with the wood by the handle n. The cutting mechanism is brought nearer and nearer to its vertical position, (shown in Fig. 3,) directly under the wood, according to the size of the shape desired. 80 While the shape of the object cut depends, as before stated, upon the shape of the pattern-wheels, the size of that shape will depend upon the nearness with which the cutting tool is allowed to approach the center of rotation of the wood.

When it is desired to produce the smallest size of a particular outline capable of being cut by a particular tool, the arbor is allowed to reach the vertical position shown in Fig. 3. 90 When larger shapes of the same outline are desired the arbor is prevented, by the stop p, from reaching this vertical position, and occupies some place between it and that shown by the dotted lines in Fig. 3. After the shape 95 is formed the wood is removed and a new piece put on.

I claim—

1. A wood-turning machine provided with the geared pattern-wheels D D upon a movable shaft, a^3 , for controlling the motion of the wood, and held in contact with the corresponding gears g g upon a stationary shaft, a^2 , for imparting motion to said pattern-wheels, as hereinbefore shown and described. 100

2. A wood-turning machine provided with the geared pattern-wheels D D, hung upon the sliding bearings $c^2 c^2$, and held down, by gravity, upon the gears g g, which rotate upon a stationary shaft, a^2 , all acting to impart rotation to a chuck, f, and holder k, or other device which holds the wood, as hereinbefore described, and for the purposes specified. 110

3. The combination of geared pattern-wheels D D, hung on a movable shaft, a^3 , and bearings $c^2 c^2$, and acted upon by gear-wheels g g, hung on a stationary shaft, a^2 , with the toothed chuck f, set-screw k, arm i, and collar j for holding and rotating the wood, all as hereinbefore shown and described. 115

4. The combination, with a rocking cutting mechanism, of a chuck, f, set-screw k, and collar j for holding the wood, rotated by geared pattern-wheels D D and their operating mechanism, all arranged as hereinbefore described, 120 and for the purposes specified.

FREEMAN HANSON.
